UNITED STATES PATENT OFFICE.

MIKE NEMES, OF FORT DODGE, IOWA.

INSULATOR.

1,032,153.

Specification of Letters Patent.

Patented July 9, 1912.

Application filed December 14, 1911. Serial No. 665,744.

To all whom it may concern:

Be it known that I, MIKE NEMES, a subject of the King of Hungary, residing at Fort Dodge, in the county of Webster and State of Iowa, have invented certain new and useful Improvements in Insulators, of which the following is a specification, reference being had therein to the accompanying drawing.

10 This invention relates to insulators, and more particularly to that type used in connection with telegraph poles.

The primary object of my invention is to furnish an insulator with positive and reliable means, in a manner as will be herein-after set forth, for clamping wires of various sizes to the insulator, in a manner that permits of the wires being readily removed.

15 A further object of this invention is to accomplish the above results by a mechanical construction that is simple, durable, and highly efficient for the purposes for which it is intended.

20 With the above and other objects in view, the invention resides in the novel construction, combination and arrangement of parts to be hereinafter specifically described and then claimed.

25 Reference will now be had to the drawing, wherein:

Figure 1 is a front elevation of an insulator in accordance with this invention, Fig. 2 is a side elevation of the same, Fig. 3 is a vertical sectional view of the insulator, 35 and Fig. 4 is a perspective view of a detached clamping member.

An insulator in accordance with this invention comprises a body 1 made of porcelain, glass or other vitreous material having 40 insulating properties. The lower end of the body 1 has a socket 2 adapted to receive the ordinary and well known type of pin used in connection with the cross arms of a telegraph pole.

45 The upper end of the body 1 is reduced, as at 3 to provide a wire support 4 and a knob or rounded off end 5. The wire support 4 has a transverse opening 6 and a longitudinal groove 7, said groove intersecting the opening 6. The groove 7 receives a wire or cable 8 and this wire or cable is adapted to be clamped into engagement with the sides of the knob 5.

50 Arranged within the opening 6 is a clamping member 9 having one end thereof screw-

threaded, as at 10 and the opposite end hook-shaped, as at 11. The hook-shaped end 11 of the clamping member 9 has a socket 12 to receive the wire or cable 8, and the side of the knob 5 is provided with a recess 13, which provides clearance for the bill 14 of the hook 11.

Screwed upon the threaded end 10 of the clamping member 9, against the wire or cable support 4, is a winged thumb nut 15, 65 said nut adjusting the member 9, whereby the hook-shaped end 11 thereof will clamp the wire or cable 8 within the groove 7. The groove 7 is of such a size that various sizes or gages of wire can be clamped in engagement with the insulator. The rounded end of the knob 5 facilitates placing a taut wire or cable in the groove 7.

70 It is thought that the utility of the insulator will be apparent without further description, and while in the drawing there is illustrated a preferred embodiment of the invention, it is to be understood that the structural elements thereof are susceptible to such variations as fall within the scope of the appended claims.

75 What I claim is:—

1. An insulator comprising a body having its upper end reduced and provided with a transversely extending opening and further 80 having an inverted L-shaped recess terminating in one end of said opening, said upper portion of said body further provided with a wire support intersecting said transverse opening, a hook-shaped clamping member having its shank extending through said opening and the free terminus of the hook projecting in said recess, the hook of said member intersecting said support and receiving the wire mounted therein, and means 85 mounted upon one end of said member and engaging the upper portion of said body for maintaining the clamping member in position thereby securing the wire to the reduced 90 upper portion of said body.

2. An insulator comprising a body having its upper end reduced and provided with a transversely extending opening and further 95 having an inverted L-shaped recess terminating in one end of said opening, said upper portion of said body further provided with a wire support intersecting said transverse opening, a hook-shaped clamping member having its shank extending through said opening and the free terminus of the 100

105

110

hook projecting in said recess, the hook of
said member intersecting said support and
receiving the wire mounted therein, and
means mounted upon one end of said mem-
ber and engaging the upper portion of said
body for maintaining the clamping member
in position thereby securing the wire to the
reduced upper portion of said body, the hook

of said member provided with a seat for the
reception of the wire.

In testimony whereof I affix my signature
in the presence of two witnesses.

MIKE NEMES.
